CHRISTIAN BACKINGER, OF SEATTLE, WASHINGTON.

HYDROCARBON-BURNER.

1,022,348

Specification of Letters Patent.

Patented Apr. 2, 1912.

Application filed November 2, 1910. Serial No. 590,374.

To all whom it may concern:

Be it known that I, CHRISTIAN BACKINGER, a citizen of the United States, residing at Seattle, in the county of King and State of Washington, have invented certain new and useful Improvements in Hydrocarbon-Burners, of which the following is a specification.

This invention relates to means for burning hydrocarbon oils as fuel in stoves, ranges or furnaces.

The especial object of my improvements is to provide a burner for use in domestic cook-stoves and ranges that will be safe, practical and economical in operation and that will be particularly adapted to the utilization of the heavier grades of petroleum oil.

With these and other objects in view, to be set forth in the following description of my improvements, the invention consists in the novel construction of an apparatus that may be installed in the fire-box of any cook-stove or range; which will generate an intense heat in said fire-box so diffused and general that it obviates the common defect among domestic oil burners known to me, of concentration of highly heated gases impinging on particular parts of the stove structure and a consequent damage thereto from unequal expansion; which will volatilize efficiently all the gaseous constituents even in heavy oils without the agency of atmospheric air, thus avoiding under all conditions of normal use any possibility of generating an explosive mixture within the apparatus; whose parts are all readily accessible and detachable to permit of convenient cleaning and inspection; in which the supply of combustible gas is constant, equable and of sufficient volume for all requirements, such as delivering heated gases of combustion through the return flues about the stove oven; and in which all the said combustible gases are consumed and utilized to the fullest extent in the generation of heat, as shown by the quantity of blue flames delivered therefrom and the absence of smoke in the combustion products.

The invention further consists in the adaptation and combination of parts, as hereinafter described, particularly pointed out in the appended claims, and illustrated

in the accompanying drawings. In said drawings, Figure 1 is a longitudinal vertical section of apparatus embodying my invention; and Fig. 2 is a horizontal view along the broken line 2--2 of Fig. 1 with the hood thereof removed and showing the heat retaining ring superposed on the grating.

In the said drawings, the reference numeral 5 designates a base-pan, preferably rectangular, as shown, and capable of being located within the fire-box of a range or cooking-stove by resting upon the grate thereof, or on any other suitable support. Such pan is desirably formed with outwardly flaring sides 6 and a bottom 7 having a centrally located boss 8 provided with a hole 9 through which protrudes an upwardly directed oil supply pipe 10 which conducts oil under pressure from a suitable source of supply, usually an elevated reservoir.

11 is a columnar support, herein shown as having rectangular vertical walls surrounding said supply pipe 10 and forming a compartment 12 therein. The walls of said support serve as a protection to the said supply pipe against undue heating with a consequent carbonization of oil therein. The air in said compartment is heated to a moderate degree, gradually warming the oil in said supply pipe and affording a reserve of warmed air in close proximity to the points of combustion. Apertures 13 at the top and bottom of said walls afford admission and egress to air within said compartment. Removably seated upon said support, and firmly held thereon by a depending flange 14, is a horizontal rectangular plate 15 having a central boss 16 with a hole 17 therein in axial alinement with the hole 9 and arranged to receive in close sliding engagement the upper end 10' of said supply pipe. The perimeter of said plate is provided with a double ridge 18 extending entirely thereabout with a corresponding groove therebetween. A rectangular hood 19 provided with depending sides 20 is arranged to be fitted over said plate and is formed with double grooves 21 with a corresponding ridge therebetween to be seated in the opposing parts 18 of the plate. Upon a small amount of residue from the oil gases gen-

- erated in the vaporizing chamber 22 comprised between the said plate and the hood being deposited at said interfitting contact, a practically gas-tight joint is effected.
- 5 Said plate is symmetrically arranged longitudinally upon each side of said boss 16 and comprises upon each side of the latter a horizontal plane surface 23 and an inverted hollow cone 24. Each said cone is provided
- 10 with an open upper end, a vertically arranged nozzle opening 25 at its lower slightly truncated end, and comprising a superheating chamber 26 therein. The outer walls of said cones may be corrugated
- 15 to promote the absorption of heat from the combustion chamber 28 and its radiation within the said superheating chamber. The upper perimeter of said superheating chamber is bounded by a wall 29 raised above
- 20 the surface 23 and of less height than said ridges 18. 30 is an extension of said wall blocking the flow of oil directly to an opening 31 in the wall and causing any oil not vaporized upon the surface 23 to take a
- 25 circuitous course, as by the passage 32 to obtain access to said superheating chamber.
- Directly beneath and about the exterior walls of each of the said superheating chambers and including the space comprised
- 30 within and between the said base-pan 5 and the hood 19 is what I term the combustion chamber wherein a combustible mixture is formed between the vapors generated within the chambers 22 and 26 and the oxygen
- 35 of the air, the vapor being under pressure. To promote the rapid combination of these elements I interpose a grating 33 of cast iron in said combustion chamber raised above the bottom 7 of the pan, as upon legs
- 40 34, to afford a space 35 therebeneath. Said grating may be formed with grate-bars 36, or in any suitable manner to provide interstices 37 communicating with the space 35. Integral with each of said gratings as shown
- 45 in Fig. 1, or superposed thereon as shown in Fig. 2, is a heat-retaining ring 38 preferably positioned approximately concentric to the nozzle 25.
- All of the said parts are or may be made
- 50 of cast metal and may be readily assembled and removed for inspection or cleaning. The hood 19 is provided with an apertured lug 39 integrally formed thereon by which it may be lifted conveniently. Dirt or residue
- 55 from the volatilized oil deposited on the plate may thereupon be readily removed. Said plate may likewise be lifted from the support 11 and the supply pipe, to which latter it is connected, by a slip-joint, as explained.
- 60 It is to be understood that I do not limit myself to the precise arrangement and combination of parts hereinabove set forth and illustrated in the drawings, as it is obvious that various modifications might or could be

made in details without departing from the spirit of the invention or from the scope of the appended claims.

The operation of the invention may be described as follows: Oil is permitted to flow through the oil-supply pipe 10 from the reservoir and may be controlled by a suitable valve (not shown) exteriorly of the stove. Oil emerging from the open end 10' of said pipe overflows over the horizontal surface 23 of the plate upon each side of said pipe. Said plate is highly heated by the combustion of gases exteriorly thereof. Volatilization and expansion of said oil ensues within the chamber 22 and the gas is forced into the superheating chamber 26 where it is further expanded by heat and emitted through the respective nozzle 25 and impinged against the grate-bars 36.

Free access of atmospheric air, as by an open draft in the stove to the combustion chamber of my apparatus, is obviated as much as practicable as I have clearly shown by experiment that best results are obtained with said devices by closing any direct draft appliance about the stove and causing the air to enter through such occasional cracks and openings as may be found therein, to break up the total amount of air entering into many currents flowing from diverse directions. By thus reducing and diffusing the amount of oxygen admitted to the combustion chamber and avoiding any direct draft thereof through the flues of the stove, but causing practically all the air entering the fire-box to unite with the hydrocarbon generated and delivered in the manner described, there results a very perfect combustion characterized by an absence from smoke and an intensely hot blue flame. The vapor generated engages with considerable force upon the grating. The vapor thereupon is divided into a great number of broken and eddying currents, some of which penetrate into the space 35 beneath the grating while others are deflected laterally against the ring 38.

No air is admitted into the vaporizing chamber, hence there is no danger of explosion. The gas is discharged from the nozzle opening without violence and is consumed in the combustion chamber without the unpleasant roaring noise frequently encountered in this class of device. In case of the flooding of said chamber by oil in greater amounts than can be volatilized, it will spread upon the surface 23 and follow the passage 32 to the opening 31 whereupon it flows into the superheating chamber 26 and, if still in excess of the vaporizing capacity of the apparatus, will flow through the nozzle 25 upon the pan-bottom 7. The oil is permitted thus to flow when it is desired to start the operation of the apparatus; the oil received in said pan being ignited to fur-

nish the required heat to the several parts, whereupon they proceed automatically to assume their several functions.

Having described my invention, what I claim as new and desire to secure by Letters Patent of the United States, is—

1. A hydrocarbon burner comprising a base pan, a grating arranged at each end thereof, an upright hollow support interposed between said gratings and communicating at its lower end with the interior of said pan, said support at its top provided with an outlet, a plate mounted upon and having a depending flange surrounding said upright, a double ridge at the perimeter of said plate, an inverted hollow cone depending from said plate at each side of said support, each of said cones formed with a vertically-disposed nozzle at its lower end and each of said cones constituting a superheating chamber, an oil supply pipe extending through said support and opening through said plate, and a hood inclosing the plate and provided with a pair of grooves in which extend said ridges.

2. A hydrocarbon burner comprising a base pan, a grating arranged at each end thereof, an upright hollow support interposed between said gratings and communicating at its lower end with the interior of said pan, said support at its top provided with an outlet, a plate mounted upon and having a depending flange surrounding said upright, a double ridge at the perimeter of said plate, an inverted hollow cone depending from said plate at each side of said support, each of said cones formed with a vertically-disposed nozzle at its lower end and each of said cones constituting a superheating chamber, an oil supply pipe extending through said support and opening through said plate, a hood inclosing the plate and provided with a pair of grooves in which extend said ridges, a wall projecting from said plate and forming a continuation of the inner face of each of the cones and formed with an opening, and an extension integral with the plate, with one end of said wall and with the inner ridge, thereby forming a conducting means for the oil to the said opening.

3. A hydrocarbon burner comprising a base pan, a vertically-disposed support arranged centrally thereof, a plate mounted upon said support and having an upturned portion at its perimeter, a pair of hollow inverted cones integral with said plate and arranged one at each side of said support and constituting superheating chambers, vertically-disposed nozzle at the lower end of each of said cones, said cones having their lower ends spaced from said base pan, a hood inclosing said plate and depending below said cones and having the upturned portion of said plate extending therein; an oil supply

pipe projecting through said pan, support and opening through said plate, and means integral with the plate for directing the oil to said superheating chambers, the top of said cover spaced from said directing means. 70

4. A hydrocarbon burner comprising a base pan, a vertically-disposed support arranged centrally thereof, a plate mounted upon said support and having an upturned portion at its perimeter, a pair of hollow inverted cones integral with said plate and arranged one at each side of said support and constituting superheating chambers, a vertically-disposed nozzle at the lower end of each of said cones, said cones having 80 their lower ends spaced from said base pan, a hood inclosing said plate and depending below said cones and having the upturned portion of said plate extending therein, an oil supply pipe projecting through said pan, 85 support and opening through said plate, means integral with the plate for directing the oil to said superheating chambers, the top of said cover spaced from said directing means, and a grating arranged within said 90 pan at each side of said support and supported above the bottom of the pan.

5. A hydrocarbon burner comprising a base pan, a vertically-disposed support arranged centrally thereof, a plate mounted 95 upon said support and having an upturned portion at its perimeter, a pair of hollow inverted cones integral with said plate and arranged one at each side of said support and constituting superheating chambers, a 100 vertically-disposed nozzle at the end of each cone and spaced from said base pan, a hood inclosing said plate and depending below said cones and having the upturned portion of said plate extending therein, an oil supply pipe projecting through said pan, support and opening through said plate, means integral with the plate for directing the oil to said superheating chambers, the top of said cover spaced from said directing 105 means, and a grating arranged within said pan at each side of said support and supported above the bottom of the pan, each of said gratings including a heat retaining ring. 110

6. A hydrocarbon burner comprising a base pan, a plate arranged over and spaced from said base pan and provided with a pair of inverted hollow depending cones each having its lower end spaced from the base pan and formed with a vertically-disposed nozzle, said plate having its perimeter provided with a pair of ridges, a cover inclosing the plate and depending below the cones and having grooves for the reception of said ridges, and means for supplying oil to the upper surfaces of said plate, said hollow cones forming superheating chambers. 120

7. A hydrocarbon burner comprising a base pan, a plate arranged over and spaced 130

from said base pan and provided with a pair of inverted hollow depending cones each having its lower end spaced from the base pan and formed with a vertically-disposed nozzle, said plate having its perimeter provided with a pair of ridges, a cover inclosing the plate and depending below the cones and having grooves for the reception of said ridges, means for supplying oil to the upper surfaces of said plate, said hol-

low cones forming superheating chambers, and means integral with the upper face of said plate for directing any oil not vaporized in a circuitous course to said superheating chambers.
